UNITED STATES PATENT OFFICE.

F. VOUILLOON AND F. TAVERNIER, OF PARIS, FRANCE.

MANUFACTURE OF YARN.

Specification of Letters Patent No. 27,014, dated January 31, 1860.

To all whom it may concern:

Be it known that we FRANCOIS VOUILLOON and FERDINAND TAVERNIER, of Paris, in the Department of the Seine and Empire of France, have invented a new and Improved Mode of Manufacturing Yarn by the Process of Felting; and we do hereby declare the following to be a full, clear, and exact description of the same, reference being had 10 to the accompanying drawing and to the letters of reference marked thereon.

Our invention consists in manufacturing yarn by the felting of the slivers, rovings, or fibrous laps produced by a wool comber, 15 carding machine, or otherwise, without the use of any of the ordinary spinning machines. By this felting process, the hairs or fibers of which the sliver or lap is composed become so intimately intermixed and 20 twisted together that the sliver is converted from a light fleecy ribbon into a thin smooth and strong yarn possessing the most favorable properties for use in the manufacture of textile fabrics.

25 In order to enable others to practice our invention we will now proceed to describe a mode of carrying it into effect which we have found most advantageous in practice.

On reference to the accompanying drawing 30 which forms a part of this specification, Figure 1, represents a plan view of a machine for the manufacture of yarn by the process of felting. Fig. 2 a vertical section of the same.

35 Similar letters refer to the same parts in both views.

In the opposite frames x and x' of cast iron or other suitable material, turn the 40 journals of the rollers a b c and d , in contact with which are a series of upper rollers e e^1 and e^2 of a larger diameter than the lower rollers, and arranged in respect to the latter in the manner illustrated in Fig. 2. These upper rollers e , e^1 , and e^2 whose journals 45 also turn in the opposite frames x and x' are entirely covered with muslin, and between the two series of rollers passes an endless apron g of muslin or other suitable material to which a proper degree of tension is 50 imparted by the weighted roller h .

The spindles of the upper rollers are coupled together by a bar o in such a manner that they can turn freely in the said bar but can have no longitudinal sliding movement in the frames independent of each other or the bar. In like manner the lower

rollers are coupled together by a bar K which is operated by an eccentric m on the shaft n , a similar eccentric p on the same shaft being arranged to operate the coupling 60 bar o and the upper rollers to which it is connected.

The shaft n is hung to brackets attached to the frame x and is driven by a strap passing round the pulley q . A bevel wheel r on the same shaft gears into a similar wheel on the shaft s which turns in the opposite frames x and x' , and which has a wheel y and pulley t , a band from the latter passing round the pulley n^2 on the spindle of 70 one of the lower rollers a . As the shaft n revolves a longitudinal reciprocating motion is imparted to the upper and lower rollers by the eccentrics p and m the upper rollers moving together simultaneously with the 75 lower rollers but the latter invariably in contrary directions to the former. At the same time a rotary motion is communicated to the spindle s and its reel y through the bevel wheels r and r' , and from this spindle 80 to the roller a through the pulleys t and n^2 , and the band passing around these pulleys. From the roller a a rotary motion is imparted to the whole of the upper and lower 85 rollers and a transversing motion to the endless apron g .

The sliver or roving u from the carding machine or wool comber, passes between the rollers x^3 and x^4 , and between the upper muslin covered rollers e e^1 and e^2 , and the 90 endless apron which passes over the lower rollers; here the sliver is subjected to the pressure between the rollers and to the reciprocating motion of the latter by which it is rolled over and over, thereby intimately 95 mixing the threads or fibers of which the sliver is composed and forming it into smooth and compact yarn which is wound round the wheel y ready to be used in the manufacture of woven or other textile 100 fabrics.

The yarn manufactured by this process, not having been submitted to any stretching, contains in a condensed form all the material of the original sliver or roving, the size 105 of the yarn depending upon the size of the sliver, and its compactness and strength depending upon the pressure and friction imparted to it by the rollers, which may be so regulated, both as regards their number and the pressure as to felt the sliver into yarn of the requisite consistency for weft or warp

and of the proper proportion and strength for knitted and other fabrics.

The felted yarn possesses many advantages to recommend it as a substitute for the stretched and twisted threads heretofore used in the manufacture of textile fabrics. It is very pliable, round, and smooth, and is made without any waste, and sufficiently strong for either warp or weft.

- 10 The operation of weaving fabrics from the felted yarn is much more rapid and easy than in weaving with the usual twisted thread, inasmuch as the felted yarn is thicker and much lighter than twisted yarn.
- 15 The action of the fuller on the fabric made of felted yarn, is more prompt than on ordinary fabrics, as the whole of the wool in the former is in the best condition for being united in one solid mass.

Although we have described a machine for 20 felting the slivers or roving of thready matters susceptible of being felted, we do not desire to limit ourselves to the use of this machine only, but

We claim as our invention and desire to 25 secure by Letters Patent—

The manufacture of yarn by submitting slivers or rovings made by a carding machine, wool comber, or otherwise, to a process of felting as herein set forth.

In testimony whereof we have signed our names to this specification, in the presence of two subscribing witnesses.

FRANÇOIS VOUILLOON.

FERDINAND TAVERNIER.
